CLAIM

The ornamental design for a measuring tool and/or toy replica thereof, as shown and described.

DESCRIPTION

FIG. 1 is a front-left isometric view of a measuring tool and/or toy replica thereof, showing my design;

FIG. 2 is a bottom-right isometric view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines throughout the Figures show portions of the measuring tool and/or toy replica thereof that form no part of the claimed design.

1 Claim, 6 Drawing Sheets
